UNITED STATES PATENT OFFICE.

WENDELL H. CALDBECK, OF DES MOINES, IOWA.

TOY SUBMARINE.

1,274,238.

Specification of Letters Patent. Patented July 30, 1918.

Application filed October 10, 1917. Serial No. 195,725.

To all whom it may concern:

Be it known that I, WENDELL H. CALDBECK, a citizen of the United States, and resident of Des Moines, in the county of 5 Polk and State of Iowa, have invented a certain new and useful Toy Submarine, of which the following is a specification.

The object of my invention is to provide a toy submarine of simple, durable and inexpensive construction.

More particularly it is my object to provide a toy submarine having a body adapted to float readily in water, and having an upright vertical keel for causing the submarine to travel ahead steadily and having laterally extending planes or wings, and having a diving plane or forwardly and downwardly extending wing for causing the device to move downwardly in the water when the 20 propeller is operated.

A further object is to provide such a device having a suitably mounted propeller, with simple and inexpensive means for imparting rotation to the propeller in the 25 water.

With these and other objects in view my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of a toy 35 submarine embodying my invention.

Fig. 2 shows a front elevation of the same.

Fig. 3 shows a transverse, vertical, sectional view taken on the line 3—3 of Fig. 1.

In the accompanying drawings, I have 40 used the reference numeral 10 to indicate generally the body of my improved toy submarine which has substantially the shape of a cylinder slightly tapered toward its rear end and tapered to a point at 11 at its 45 forward end.

The body 10 may be made of wood or any suitable material, and in any suitable way, so that it will readily float in water.

Mounted in the lower part of the body 50 10, and extending from front to rear thereof is a plate 12, which above and in front of the wings hereinafter mentioned, forms a keel. The plate 12 is provided at its lower forward corner with an opening 13 to which 55 a string or the like may be attached.

On opposite sides of the plate 12 are lat-

erally extending wings 14, which are inclined from the rear end of the submarine forwardly and downwardly, as shown in Fig. 1, and are also curved from the plate 12 60 upwardly and outwardly, as shown in Fig. 3.

The wings 14 are moved downwardly and forwardly at 15 at their forward ends, and may at their forward ends be formed integral with each other if desired.

At their adjacent edges, during the greater portion of their length and except at their forward ends, the wings are provided with flat parallel downwardly extending flanges 16 forming a keel. The flanges 16 have at 70 their rear ends downward extensions 17, and provided at their lower edges with spaced, downwardly extending bearings 18.

Mounted in the bearings 18 is a short shaft 19 having on its forward end a hook 75 20, and on its rear end spaced from the rearward bearing 18, a propeller 21.

Mounted on the shaft 19 between the propeller 21 and the rearward bearing 18 is a suitable bushing or the like, which may 80 consist of an ordinary bead 22. The downwardly and forwardly extending portion 15 of the wings 14 is provided with a central opening 23 which permits water to pass through during the progress of the submarine and assists in causing the submarine 85 to travel forwardly steadily and with uniform regular motion.

Secured to the portion 15 is a hook device or the like 24. A rubber band or other suitable resilient band 25 may be mounted on the hooks 24 and 20. Extending upwardly from the top body 10 is a rod or the like 26 on the upper end of which is a small cylinder 27, having the appearance of a 95 periscope.

In the practical use of my improved toy submarine the operator rotates the collar 21 with his fingers for twisting the resilient member 25. By holding the propeller 100 against movement, the submarine is lowered into the water and released. The resistance of the water will limit the speed of the propeller and the rotation of the propeller will drive the submarine forwardly.

The arrangement of the member 21 will 105 cause the submarine, during the rotation of the propeller, to move downwardly in the water for a certain distance, and thereafter the submarine will travel horizontally 110 in the water. When the motion of the propeller stops, the submarine will

gradually float to the top, where the periscope 27 will project out of the water.

The arrangement of the wings 14 inclined downwardly slightly from their rear ends, 5 and with the sharpened inclination at their forward ends is such as to cause the submarine to move downwardly in the water when the submarine is placed in the water at the surface.

10 The plate 12 and the flanges 16 form a keel and cause the submarine to travel straight forwardly.

The hole 23, I find also assists in causing the proper steady movement of the submarine. 15

The parts are of very simple construction, and the entire device can be made rapidly and at a small expense.

It will be noted that the plate 12 may be 20 placed in a saw kerf in the body 10, where the body 10 is made of wood, and that the wings may be made of a single piece of metal split along a central line, except at their forward end, and bent to the proper 25 shape.

It should be mentioned in this connection that the wings 14 are narrower from side to side at their rear end, than at the central portion. It should be noted also that the 30 portion 15 is tapered from its side toward the front.

It may be mentioned in this connection that the shape of the forward ends of the wings 14 is of considerable importance.

35 It will be noticed that they come together and are tapered, so that such forward ends incline downwardly and forwardly from the body of the submarine, and also are tapered toward a curved nose in front. This construction is important insomuch as the submarine is usually used in a bath tub, tub or tank with a curved wall. When the submarine travels along under the water the nose or front of the wings 14 strikes the wall and 40 being curved and flared, tends to deflect the submarine and turn it to a path along side the wall where it can travel properly. Where the submarine keeps on going and strikes the bottom, the front ends 15 of the 45 wings 14 form a nose, which touches the bottom of the tub or the like, and this causes the submarine to come down to an even keel or horizontal position whereupon it will travel along the bottom in that position.

55 Some changes may be made in the construction and arrangement of the parts of my improved submarine, without departing from the essential features and purposes of my invention, and it is my intention to cover 60 by the patent to be issued upon my application, any modified forms of structure or

use of mechanical equivalents, which may be reasonably included within the scope of my claims.

I claim as my invention:

1. In a toy submarine, a body adapted to float in water, having a tapered front end, a plate secured to said body at the forward part thereof, and extending from the lower end thereof rearwardly, side wings extending from the forward portion of said body at the lower part thereof rearwardly and slightly upwardly, said side wings being also curved from the lower central portion of said body upwardly and laterally, a 75 downwardly inclined member at the forward end of said side wings forming a diving plane, a keel below said side wings and below the center of said body, a shaft at the lower portion of said device, a propeller thereon, a hook member on said diving plane, and a resilient device connected with said hook member and with said shaft. 80

2. In a toy submarine, a body adapted to float in water, having a tapered front end, 85 side wings extending laterally and upwardly from the central lower part of said body, and inclined from their forward ends upwardly and rearwardly, a central, vertical plate extending downwardly from the forward portion of said body, a diving plane curved downwardly from the forward ends of said side wings, and tapered toward its forward end, said diving plane having a central opening. 90

3. In a toy submarine, a body adapted to float in water, having a tapered front end, side wings extending laterally and upwardly from the central lower part of said body, and inclined from their forward ends upwardly and rearwardly, a central, vertical plate extending downwardly from the forward portion of said body, a diving plane curved downwardly from the forward ends of said side wings, and tapered toward its 105 forward end, said diving plane having a central opening, a downwardly extending member at the rear end of said device, a shaft rotatably mounted therein, a resilient member secured to said shaft and connected 110 with said diving plane, and a propeller on said shaft.

4. In a toy submarine, a boat adapted to float in water having a tapered front end, side wings extending laterally from the lower portion of said boat, said side wings being curved downwardly and forwardly at their forward ends, and tapered toward a central point in front, the forward ends of said wings being slightly curved. 115

Des Moines, Iowa, May 18, 1917.

WENDELL H. CALDBECK.
